COMBINED CHILD'S CUP AND COVER

Gerald K. Geerlings, New Canaan, Conn.

Application October 19, 1948, Serial No. 149,183

Term of patent 7 years

(Cl. D44—9)

To all whom it may concern:

Be it known that I, Gerald K. Geerlings, a citizen of the United States, residing in New Canaan, in the county of Fairfield and State of Connecticut, have invented a new, original, and ornamental Design for a Combined Child's Cup and Cover, of which the following is a specification, reference being had to the accompanying figures of the drawing forming part thereof.

Fig. 1 is a perspective view of a combined child's cup and cover, showing my new design;

Fig. 2 is an exploded perspective view;

Fig. 3 is an elevational view;

Fig. 4 is a vertical sectional view;

Fig. 5 is a top plan view; and

Fig. 6 is a bottom plan view thereof.

I claim:

The ornamental design for a combined child's cup and cover, as shown.

GERALD K. GEERLINGS.
